VAPOR CONDENSING DEVICE

Everett N. Wood, Mason City, Iowa

Application March 22, 1935, Serial No. 12,427

9 Claims. (Cl. 257—25)

The present invention relates to devices for condensing vapors, and more particularly to those arising in the cooling systems of internal combustion motors and the like, and especially in the cases of using anti-freezing solutions having lower boiling points than water.

The heat from the internal combustion motor raises the temperature of the cooling liquid sufficiently that some of the liquid becomes lost by vaporizing, the vapors ordinarily passing out through the overflow pipe. That necessitates frequent replenishment. This is especially so during the cold months when the cooling fluid contains the anti-freezing components such as alcohol or the like, the anti-freezing component vaporizing very readily.

The present invention comprehends the provision of a novel device for condensing such vapors and returning the condensate to the body of the cooling liquid, thus preventing or reducing to a minimum loss of the vapors.

In the specific embodiment selected to illustrate the invention the vapors pass upwardly into the condensing device by way of a plurality of tortuous paths, or passages, whereby the vapor may be subjected to an extended cooling surface so as to be thoroughly condensed or converted to a liquid state, the liquid or condensate then flowing back through the vapor inlet and into the body of the cooling fluid or liquid.

Another object of the invention is to provide novel means for acting as a vapor lock or trap so located between the overflow pipe and the vapor outlet side of the condensing device as to prevent free escape of the vapors and to prevent a too rapid movement of the vapors in the condensing part of the condensing device thus affording an efficient conversion of the vapor into liquid in the condensing device.

A further object of the invention is to provide a novel condensing device having cooling means such as fins, projections or the like for absorption of heat.

The invention also comprehends novel means for preventing complete removal of the condensing means.

Other objects, capabilities, advantages, features and the like are comprehended by the invention as will later appear and as are inherently possessed by the invention.

Referring to the drawing;

Fig. 1 is a view in perspective of a device constructed in accordance with the invention;

Fig. 2 is a view partly in side elevation and

partly in section of the same mounted on a vehicle radiator;

Fig. 3 is a bottom plan view of the device;

Fig. 4 is a sectional view taken in a plane represented by line 4—4 in Fig. 2 of the drawing; 5

Fig. 5 is a view in side elevation of a side of the inside of the device; and,

Fig. 6 is a similar view of the opposite side;

Referring more in detail to the drawing, the device selected to illustrate the invention is shown in connection with an automotive vehicle radiator shell 1 connected in any suitable manner to the front end of the hood 2. The shell 1 has an opening in which is located the upper end of a radiator filler neck 3 the lower end of which is connected to and communicates with the radiator top tank 4. In the neck 3 and tank 4 is located a portion of the usual overflow pipe 5.

The condensing device comprises generally two members 6 and 7 which are made of suitable heat conducting material such as metal, the members 6 and 7 having base portions 6^a and 7^a.

These parts may be united in any suitable manner as by soldering, brazing, welding, etc. The outside walls of the members 6 and 7 are provided with heat radiating or heat absorbing fins 24 so arranged or disposed as to permit a flow of air through the spaces between the fins when the vehicle is moving. The inner walls of the members 6 and 7 are provided with baffles 23 and 22 respectively which may be of any form such as fins, walls, projections or the like. These baffles are disposed at different angles so that the baffles of one part will cross the baffles of the other part as is clearly shown in Fig. 2, thus providing for a multitude of tortuous passages or paths from the channels between a set of baffles, to and into the channels between the other set of baffles, the edges of one set being proximate to or contacting with the edges of the other set at 40 the crossing points, or may even be united at the crossing points in any suitable manner.

At the lower ends of the baffles 22 and 23 are provided openings 25 for the relief of any sediment which might gather in the condenser so that the sediment may be carried down with the condensate to and through the port 20 and into the interior of the radiator.

It will be noted that the chamber of the condenser has an inclined lower wall 26 which also constitutes the upper wall of the return passage portion 27, and an upwardly inclined end wall 28 which constitutes the inner wall of the return passage portion 29. These passage portions 29 and 27 taper toward the outlet 18. It also will 55

be noted that the wall 26 is not parallel to the upper wall 38 of the condenser body and hence the cross-sectional area of the chamber varies from its inlet to its outlet. In other words the device 5 broadly is a passage having portions which vary or change in cross-sectional area the rate of change in one portion being different from that in another portion.

To the base 6—7^a is secured a filler cap clip 10 8 by any suitable means such as screws, rivets, etc. together with an interposed gasket 16 and a sealing or compression ring 15 of yieldable material such as rubber or the like. Registering apertures are provided in the clip 8, gasket 16 and the base 15 of the condenser to form a vapor passage 20 for the entry of the vapor from the upper part of the radiator into the chamber provided in the condensing device between the parts 6 and 7.

A keeping means may be used to prevent the 20 complete removal of the condensing device when it is moved in open position to pour in some of the cooling liquid when replenishing or otherwise. This means comprises a resilient member 12 which may be curved to a size as to permit it to 25 pass through the opening in the upper end of the neck 3, and then permitted to expand to press against the inner wall of the neck 3. To the spring clip 12 is connected a flexible member 13, such as a cable, chain or the like, the member 13 30 being connected swivelly at 17 to the cap clip 8 as shown in Fig. 5. To bring the spring clip 12 into locking position, the cable or chain 13 is pulled upwardly to cause the spring clip 12 to slide upwardly into the annular space or recess 35 provided under the inturned lip or flange 3^a formed at the upper end of the filling neck 3, the spring clip 12 pressing outwardly against the inner surface of the upper end of the neck 3 to frictionally hold the clip 12 in place as shown in 40 Fig. 2. The cable or chain 13 is sufficiently long to permit the opening of the neck 3 when raising the condensing device, the base 6—7^a acting as the closing cap for the neck 3 and taking the place of the usual closing cap. The base is connected in the usual way, that is, by the same 45 means as is usually used to connect the usual closure cap, which in this case, is replaced by the condenser base.

To the condenser base is connected an outlet 50 nipple 18 for the discharge of vapors if any succeed in passing, without condensation between the walls of the condensing device, into the passage 21^a formed in the condensing device.

To the nipple 18 is connected a flexible duct 9, 55 such as a rubber hose or the like, by a spring clip or clamp 14, the other end of the duct being likewise connected by a spring clip or clamp 14^a to an end of a fitting 11 secured to the upper end of the overflow pipe 5 by means of a coupling 10 having 60 a packing 19. The duct 9 is sufficiently long to permit the raising of the condenser when pouring in a liquid, and also to form a trap 9^a when the condenser is in closed position. This trap will 65 serve as a vapor seal or trap when it contains a liquid condensate to prevent passage of the vapors that may pass through the condenser, if any succeed in passing. Moreover it serves the purpose of holding back the rate of flow of the vapors through the condensing device thus preventing the vapors from passing too rapidly. Such retardation of the vapors will afford complete and efficient condensation so that there will be no escape of vapors. The condenser is so designed as to condense all the vapors that may be 70 formed under the usual conditions, but should the

motor become unduly overheated, some vapors may pass and condense in the trap 9^a to form a liquid seal against the loss of vapors in the overflow pipe 5. This increases the efficiency of the device. 5

In operation, whatever vapors that are formed will pass up through the passage 20 into the spaces between the baffles 22 and 23, and will move slowly in tortuous paths or passages toward the upper rear part of the condenser. The air flowing by the exterior cooling means 24 will cause a cooling of the baffles 22 and 23 and hence the vapors passing tortuously and slowly in the condenser, will be cooled and condensed. The vapors condense and collect at the lower portions of the channels formed between the baffles 22 and 23 to flow back to the passage 20 to return to the liquid in the upper part of the radiator. 10 15

While I have herein disclosed an illustrative embodiment of the invention, it is to be understood that the latter is not limited thereto but comprehends other constructions, details, arrangements of parts, features and the like, without departing from the spirit of the invention. 20

Having thus disclosed the invention, 25

I claim:

1. A vapor condensing device comprising a body provided with a series of criss-crossing baffling elements to produce a tortuous passage for the movement therein of the vapors to be condensed, and cooling means on the body for absorbing heat. 30

2. A condensing device for condensing vapors comprising a body having a chamber in which are crisscrossing baffling means so arranged and constructed as to provide a plurality of tortuous passages for the vapors. 35

3. A condensing device for condensing vapors comprising a body having a chamber in which are oppositely disposed baffling means at an angle to each other and crossing at a plurality of points to provide a plurality of tortuous passages for the vapors. 40

4. A condensing device for condensing vapors comprising a body having a chamber in which are oppositely disposed baffling means at an angle to each other and crossing at a plurality of points to provide a plurality of tortuous passages for the vapors, and cooling means on said body for absorbing heat. 45

5. A condensing device for condensing vapors comprising a body having a chamber on the opposite walls of which are located baffling means with the means on one wall at an angle to the means of the other wall to provide a tortuous passage for the vapors, the edges of the means of one wall crossing at spaced points the edges of the means of the other wall. 50 55

6. A condensing device for condensing vapors comprising a body having a chamber on the opposite walls of which are located baffling means with the means on one wall at an angle to the means of the other wall to provide a tortuous passage for the vapors, the edges of the means of one wall crossing at spaced points the edges of the means of the other wall, and cooling means 60 65 on said body for absorbing heat.

7. A condensing device for condensing vapors arising from a body of cooling liquid for an internal combustion motor having a radiator and overflow pipe, comprising a body having a chamber provided with an inlet and an outlet, and a flexible duct connected with said outlet and with the overflow pipe for preventing escape of vapors from said body of liquid in said radiator. 70

8. A condensing device for condensing vapors 75

- arising from a body of cooling liquid for an internal combustion motor having a radiator and overflow pipe, comprising a body having a chamber provided with an inlet and an outlet, and a flexible duct connected with said outlet and with the overflow pipe for preventing escape of vapors from said body of liquid in said radiator, said connecting means having means for controlling the rate of movement of the vapor in said chamber to obtain effective condensation.
9. In a condensing device for vapors arising from a body of cooling liquid for an internal combustion motor having a radiator provided with
- 5 a filling opening at the top, a keeping means having a flexible connecting member connected to said condensing device and a resilient member connected to said flexible connecting member, said radiator having an inturned flange at said filling 5 opening, said resilient member being contractible for insertion through said filling opening and expansible for pressing contact with the side walls of the radiator beneath said inturned flange whereby said resilient member engages said flange 10 when said condenser is raised to limit the extent of raising said condenser.
